UNITED STATES PATENT OFFICE

2,018,709

BOILER CONSTRUCTION

Eugene Callahan, Devils Lake, N. Dak.

Application December 13, 1933, Serial No. 702,129

5 Claims. (Cl. 122—271)

This invention relates to boilers and particularly to a construction and arrangement for generating and delivering steam for use in heating systems or for other purposes.

One object of the present invention is to provide a boiler in which steam is quickly generated.

Another object of the invention is to provide a novel construction and arrangement for superheating the steam and delivering it for use in a substantially dry condition.

Another object of the invention is to provide a structure wherein portions of the device may be disassociated from other positions thereof for making necessary repairs or for other purposes without disturbing the remaining portion of the structure.

A further object of the invention is to provide a novel construction in boilers, made up principally of pipe fitting of standard construction, to facilitate the repair and replacement of various portions of the boiler structure, as may be required.

A still further object of the invention is to improve devices of the character described in sundry details hereinafter referred to and particularly pointed out in the appended claims.

One embodiment of the present invention is shown for illustrative purposes in the accompanying drawings, in which:

Fig. 1 is a perspective view, partly in section, of a boiler construction illustrating an embodiment of the present invention;

Fig. 2 is a transverse elevational sectional view through the structure illustrated in Fig. 1, and taken substantially as indicated by the line 2—2 thereof; and

Fig. 3 is a longitudinal sectional elevational view taken substantially as indicated by the line 3—3 of Fig. 1.

The illustrative embodiment of the present invention as shown in the drawings, comprises a housing 5 formed preferably of refractory material and providing a fire box and heating chamber 6 within its interior, and having passages 7 and 8 formed preferably adjacent the lower portion thereof, the said passages being arranged in substantially parallel relation at opposite sides of the fire box, shown in the present instance as being provided with a grate 9 mounted in the housing, the passages 7 and 8 terminating adjacent their rear ends in diagonally extending portions 11 communicating with a stack or stack connection 12 for discharging the products of combustion from the device.

Mounted in the housing 5 preferably at opposite sides of the heating chamber 6 formed therein, and adjacent the passages 7 and 8, are a pair of headers formed preferably of standard pipe fittings and indicated as a whole by the numerals 13 and 14, the forward ends of the headers being connected by means of conduits 15 with a pipe 16 for supplying water or other heat exchange medium to said headers.

Mounted respectively at opposite sides of the heating chamber 6 formed within the housing 5 and communicating with the headers 13 and 14, are a plurality of vertically disposed water containers 17 having off-set portions 18 positioned inwardly with respect to the main body portion of 15 the water container and extending outwardly of the housing 5, preferably through the upper or top portion 19 thereof.

The water containers including their off-set portions are of substantially like construction, and it is thought that a description of one will suffice as a description of all of the containers, and, as clearly illustrated in Figs. 1 and 2, the upper and lower ends of the main body portion of the container are provided with apertured closure members 21 and 22, respectively, (Figs. 1 and 2) in which are mounted the upper and lower ends, respectively, of a flue 23 extending longitudinally through the main body portion of the container and communicating at its upper end with the heating chamber, and at its lower end with one or the other of the passages 7 and 8 for conducting the products of combustion in a downward direction from the heating chamber to the passages 7 and 8, and thence through the diagonal portions 11 of the passages to the stack connection 12, thus providing additional heating surface for the water within the containers 17, it being understood that the water in the containers may be maintained at substantially the level indicated to provide a steam chamber adjacent the upper ends of the off-set portions 18 of the water containers.

Mounted above the heating chamber preferably outside the housing 5, is a collecting drum or steam dome 24, and for conducting steam from the respective chambers formed at the upper ends of the off-set portions 18 of the water containers to the steam dome, a plurality of conduits, indicated as a whole by the numeral 25, and including coils 26 positioned in the heating chamber, are provided, one end of the conduits 25 communicating with the upper ends of the off-set portions 18 of the water containers through apertured closure members 27, and the

opposite end of the conduits communicating with the steam dome 24, the conduits communicating with the water containers at one side of the heating chamber being adapted to enter the steam dome at the side thereof opposite the last mentioned containers, as clearly shown in Fig. 2 of the drawings.

It will be observed from the foregoing description that the present invention provides a construction and arrangement, whereby heat is applied not only to the surface of the water containers 17, but also may be transmitted to the fluid therein through the flues 23 in a manner to quickly generate steam in the upper ends of the off-set portions 18, and that by reason of the coils 26 in the conduits 25 being positioned within the heating chamber, the steam in passing from the off-set portions 18 to the steam dome 24, is super-heated in a manner to deliver substantially dry steam to the dome for whatever use the steam may be employed, thereby increasing the efficiency of the boiler construction. It will be observed also that by reason of the headers, water containers and conduits being constructed of standard pipe fittings, the various portions of the structure disclosed may be readily removed for repairing, and may be readily replaced with new fittings when necessary.

Obviously, the present invention is not limited to the precise construction and arrangement shown and described, as the same may be variously modified. Moreover, all the features of the present invention need not be used jointly, as the same may be used to advantage in variously different combinations and sub-combinations.

What I claim as new and desire to secure by Letters Patent is:

1. An apparatus of the class described comprising a housing having a fire box and heating chamber therein, said housing having a pair of passages positioned respectively at opposite sides of the fire box, a stack connection communicating with said passages, a pair of headers positioned respectively at opposite sides of the fire box, a plurality of independent water containers operatively related to and extending upwardly from the respective headers, a plurality of flues extending through the respective water containers, said flues communicating at one of their ends with said heating chamber and at their opposite ends with said passages for conducting the gases of combustion from said chamber to said passages, a steam dome positioned above said heating chamber, and a plurality of conducting means positioned in said chamber and communicating at their opposite ends with the respective containers and with said dome for conducting steam through the heating chamber in its passage from the containers to the dome.

2. An apparatus of the class described comprising a housing having a fire box and heating chamber therein, said housing having a pair of passages positioned respectively at opposite sides of the fire box adjacent the lower portion of the housing, a stack connection communicating with said passages, a pair of headers positioned respectively adjacent the respective passages at opposite sides of said fire box, means for supplying water to said headers, a plurality of spaced independent water containers operatively related to and extending upwardly from the respective headers, a plurality of flues extending longitudinally through the respective water containers, said flues communicating at one of their ends

with said heating chamber and at their opposite ends with said passages for conducting the gases of combustion from said chamber to said passages, a steam dome positioned above said heating chamber, and a plurality of conducting means positioned in said chamber and communicating at their opposite ends with the respective containers and with said dome for conducting steam through said heating chamber to super-heat the steam in its passage from the containers to said dome.

3. An apparatus of the class described comprising a housing having a fire box and heating chamber therein, said housing having a pair of passages positioned respectively at opposite sides of the fire box adjacent the lower portion of the housing, a stack connection communicating with said passages, a pair of headers positioned respectively adjacent the respective passages at opposite sides of the fire box, means for supplying water to said headers, a plurality of spaced vertically disposed independent water containers communicating with and extending upwardly from said headers and having offset portions extending outwardly of the housing, a plurality of flues extending longitudinally through the respective water containers, said flues communicating at one of their ends with said heating chamber and at their opposite ends with said passages for conducting the gases of combustion from said chamber to said passages, a steam dome positioned above said heating chamber outside said housing, and means including a plurality of coils positioned in said chamber and communicating at their opposite ends with the respective containers and with said dome for conducting steam through said heating chamber to super-heat the steam in its passage from the containers to said dome.

4. An apparatus of the class described comprising a housing having a fire box and heating chamber therein, said housing having a pair of passages positioned respectively at opposite sides of the fire box adjacent the lower portion of the housing, a stack connection communicating with said passages, a pair of headers positioned respectively above and adjacent the respective passages at opposite sides of said fire box, means for supplying water for said headers, a plurality of spaced vertically disposed independent containers communicating with and extending upwardly from said headers and having offset portions extending outwardly above said housing, a plurality of flues extending longitudinally through the respective water containers in spaced relation thereto, said flues communicating at their upper ends with said heating chamber and at their lower ends with said passages for conducting the gases of combustion in a downward direction from said chamber to said passages, a steam dome positioned above said heating chamber outside said housing, and means including a plurality of coils positioned in said chamber and communicating at one of their ends with the respective upper ends of the offset portion of said containers and at their opposite ends with said dome for conducting steam through said heating chamber to super-heat the steam in its passage from the containers to said dome.

5. An apparatus of the class described comprising a housing of refractory material having a fire box and heating chamber therein, said housing having a pair of passages positioned respectively at opposite sides of the fire box, a stack connection communicating with said passages,

- a pair of headers comprising standard pipe fittings positioned respectively at opposite sides of the fire box, a plurality of independent water containers comprising standard pipe fittings and having main body portions operatively related to said headers and having off-set portions extending outwardly of said housing, apertured closure members secured to the ends of said main body portions and to the outer ends of said off-set portions of the water containers, a flue extending longitudinally through each of said body portions and having its ends open and positioned in the apertures of the members secured to said body portions for conducting the gases of combustion from said heating chamber to said passages, a steam dome positioned above said heating chamber, and a plurality of conducting means comprising standard pipe fittings and including a plurality of coils positioned in said heating chamber, said coils communicating respectively at one of their ends with said off-set portions of the water containers adjacent the apertured closure members secured thereto and at their opposite ends with said dome for conducting steam through said heating chamber to super-heat the steam in its passage from the containers to said dome.

EUGENE CALLAHAN.
